NATHAN M. SLOVER, OF BRECKENRIDGE, TEXAS

GRAB TOOL

Application filed December 9, 1929. Serial No. 412,753.

This invention relates to a tool particularly useful for retrieving articles which have been lost or accidentally dropped into wells during the process of drilling or cleaning out, such articles consisting of bits, reamers, pieces of rock, wrenches, hammers, and other débris which may have gotten into the well. While particularly adapted for the use set forth above, my tool may be used for any other purpose to which it is applicable.

It is the principal object of my invention to provide a grab tool for the purposes set forth which will perform the functions intended efficiently and in an expeditious manner.

Another object of my invention is to provide a tool of the class described which is solid and substantial, yet relatively cheap to manufacture.

These and other objects will be apparent to one skilled in this art after a study of the specification taken in connection with the annexed drawings, wherein:

Figure 1 is a sectional view through the tool.

Figure 2 is a sectional view through the tool taken at right angles to Figure 1.

Figure 3 is a sectional view through the tool the same as Figure 1, but after the gripping jaws have been tripped.

Figure 4 is a top view of one of the gripping jaws.

Figure 5 is a plan view of the jaw.

Figure 6 is a plan view of the hanger plate.

Figure 7 is a view looking down from the top of the part shown in Figure 8.

Figure 8 is an elevational view of part of the control mechanism of the tool.

Figure 9 is a plan view looking down on the part shown in Figure 10.

Figure 10 is an elevational view of the tripper or trigger.

Figure 11 shows two views of the tripper pull bars.

Figure 12 shows two views of the tripper stem locking arms.

Referring now to the details, wherein like numbers refer to corresponding parts in the various views, 1 comprises the main part or casing of the tool, and this casing is prefera-

bly made of steel pipe of a suitable thickness, preferably cut smooth and square at the point 2, thereby providing shoulders for upset ends of the grab jaws 3 which are pivoted at 4 to lugs 5 riveted or welded to the side-walls of the tube 1.

The upper end of the tubular member 1 is provided with a suitable fitting 6 which is fastened to the tube 1 in any satisfactory manner as by screw thread 7. The free end of the member 6 is preferably provided with a pipe-thread 8 to which a pipe or nipple may be fastened for the purpose of raising and lowering the tool into the well.

Near the lower end of the pipe 1, is mounted an annular plate 9. As shown in the drawings, a suitable number of lips 10 may be punched inwardly from the wall of pipe 1, and the plate 9 then dropped into the pipe and lips 11 pushed under the plate, and if desired, the plate may be welded at the point 12 to the tube 1; or as an alternative construction, the lower part 13 of pipe 1 may be made as a separate ring and welded to the annular plate 9 and the lower portion of the pipe 1.

Resting on the annular hanger plate 9, is a circular retaining member, preferably in the form of a piece of tubing 36. Positioned between the retaining member 36 and the wall 14 of the pipe 1, is a compression spring 14 which rests on the hanger plate 9. The upper end of the spring 14 engages an abutment plate 15 adjustably carried on the threaded end of a pin 16 which is fastened in any satisfactory manner as by a threaded collar 17, to a centrally positioned tube 18. To the lower end of the tube 18, is fastened a disc 19. The upper surface of the disc 19 is provided with lugs 20, one pair of which are disposed on opposite sides of the axial center of the disc. The lugs 20 support a pin 21 for a purpose to be later described.

On the lower side of the disc 19, are a plurality of lugs 22 to which are pivotally fastened pull bars 23, the opposite ends of which are attached by means of holes 24 to the gripping jaws 3.

Positioned between the jaws 3, is a tripper which may take different forms, but as shown,

it is in the form of a plate 25 to which is fastened an upwardly extending stem 26. To reduce the weight, the stem 26 is preferably made of tubing and has its upper end closed by a plate 27 on which rests a spring 28, the upper end of which abuts against the lower portion of the pin 16. The tube 18 is slotted on opposite sides at 29 to allow a pair of tripper locking arms 30 to pass therethrough. The locking arms 30 are pivoted at 31 to the stem 26 and pass through slots in the stem 26 corresponding to the slots 29 in the tube 18.

The outward ends of the arms 30 extend respectively between a pair of the lugs 20 and under the pin 21, which together may be generally referred to as a retaining device, and when the tool is set in open position, the ends 32 of the arms 30 extend into oppositely arranged holes in the lower end of the retaining member 36, thereby locking the arms in the position as shown in Figure 1, and consequently holding the jaws 3 in open position.

The jaws 3 are provided with pins 33 which are preferably pointed and hardened to grip the device which is to be grabbed by the jaws.

In order to set the tool in grabbing position, there are provided openings 34 in the wall of the tubular member 1, through which openings a suitable implement may be passed which will engage the upper end of the pin 16 to force the same, together with the tube 18 and the plate 19, downwardly against the spring 14 until, due to the spring 18, the ends 32 of the locking arms 30 drop into the holes in the retaining member 36, all as shown in Figure 1, thereby setting the tool in grabbing position to be dropped into the well.

Coming now to the grabbing operation of the tool, it will be readily understood that when the tool is dropped into the well, the object strikes the tripper 25 and pushes the stem 26 upwardly, thereby pulling the locking arms 30 out of the holes in the retaining member 36, allowing the spring 14 acting against the plate 15, to lift the tube 18 and plate 19 upwardly to the position shown in Fig. 3. The upward movement of the plate 19 acting through the levers 23, pulls the jaws to the closed position as shown in Figure 3, thereby grabbing the object, and the tool is then pulled up out of the well and reset as already explained.

It will be apparent that numerous changes in the details of my invention may be made; for example, if deeper fishing is desired, the tripper plate 25 may be fastened to a collar 35 which in turn may be adjustable on the stem 26, which in this case is cut off at the collar 35.

Since these variations in the constructional details may be made, I do not wish to be unduly limited in the interpretation of the appended claims.

Having thus described my invention, what I claim is:

1. A grab tool including; a tubular member having an operating member attached to one end thereof, a hanger plate fastened within the tubular member near its other end, a circular retaining member anchored to said plate and having oppositely positioned holes in its wall near the plate, a compression spring resting on said plate and extending upwardly between said retaining and tubular members, a centrally positioned tube having a disc fastened to its lower end, said disc having guide devices on its upper side adjacent the holes in said retaining member and lugs on its lower surface, jaws pivoted at the lower end of said tubular member, levers connected between said jaws and the lugs on said disc, a tripper positioned between said jaws and having a stem extending upwardly within said central tube, locking arms pivoted to said stem and normally extending through the wall of the central tube through said guide devices on the disc into the holes in said retaining member, a spring held within said central tube and pressing against said tripper stem and normally holding said locking arms in locking position whereby said jaws are held in open position, a pin fastened to the upper end of said central tube, and an abutment plate adjustably carried on said pin for tensioning the first mentioned compression spring.

2. A grab tool including; a tubular member having an operating member attached to one end thereof, a hanger plate fastened within the tubular member near its other end, a circular retaining member anchored to said plate and provided with lever retaining means, a spring having its lower end positioned between the retaining and tubular members, a centrally positioned tube having a disc fastened to its lower end, said disc having guide devices adjacent said lever retaining means, lugs on said disc, jaws pivoted at the lower end of said tubular member, levers connected between said jaws and the lugs on the disc, a tripper positioned between said jaws and having a stem extending upwardly within said central tube, locking arms pivoted to said stem and extending through the wall of the tube and through said guide devices and adapted to engage said lever retaining means, a spring held within said central tube and pressing against said tripper stem and acting to normally hold said locking arms in engagement with said lever retaining means whereby said jaws are held in open position, a pin fastened to the upper end of said central tube, and an abutment plate adjustably carried on said pin for tensioning the first mentioned compression spring.

3. A grab tool including; a tubular member having an operating member attached to one end thereof, a hanger plate fastened with-

in the tubular member near its other end, a circular retaining member anchored to said plate and provided with lever retaining means, a spring having its lower end positioned between the retaining and tubular members, a centrally positioned tube having a disc fastened to its lower end, said disc having guide devices adjacent said lever retaining means, lugs on said disc, jaws pivoted at the lower end of said tubular member, levers connected between said jaws and the lugs on the disc, a tripper positioned between said jaws and having a stem extending upwardly within said central tube, locking arms pivoted to said stem and extending through the wall of the tube and through said guide devices and adapted to engage said lever retaining means, a spring held within said central tube and pressing against said tripper stem and acting to normally hold said locking arms in engagement with said lever retaining means whereby said jaws are held in open position, said jaws being provided with inwardly projecting pins to grip an article, and said tubular member being provided with at least one opening adjacent the upper end of said central pin whereby an implement may be inserted therethrough so as to act on the pin to reset the tool substantially as described.

4. A grab tool including; a tubular member with means for moving the same, grab jaws pivoted to the lower end of said member, a tripper positioned between said jaws and having an upwardly projecting stem, a movable tube having one end extending over said stem, a disc carried by said tube and having guide devices thereon, levers extending from the disc and fastened to said jaws adjacent said pivot points, said tubular member carrying within means for retaining lever ends, locking arms fastened to said stem and projecting through said tube and adapted to be guided by said guide devices into engagement with said lever retaining means, a spring within said tube acting on said stem, a spring supported within said tubular member, and means for transmitting the force of said last mentioned spring to said movable tube as and for the purpose described.

5. A grab tool including; a tubular member with means for moving the same, grab jaws pivoted to the lower end of said member, a tripper positioned between said jaws and having an upwardly projecting stem, a movable tube having one end extending over said stem, a disc carried by said tube and having guide devices thereon, levers extending from the disc and fastened to said jaws adjacent said pivot points, said tubular member carrying within means for retaining lever ends, locking arms fastened to said stem and projecting through said tube and adapted to be guided by said guide devices into engagement with said lever retaining

means, a spring within said tube acting on said stem, a spring supported within said tubular member, and means for transmitting the force of said last mentioned spring to said movable tube as and for the purpose described, said tubular member being provided with at least one opening whereby an implement may be applied to said movable tube to reset the tool to open position.

6. A presetting grab tool including; a hollow member having means for moving the same, arcuately formed grab jaws pivoted to the lower end of the hollow member and normally having an abutment on the end of said hollow member, means for holding said jaws in said normal position including cooperative locking parts, a tripper positioned within the confines of said jaws and having a part extending upwardly, locking means carried by said tripper part for engaging said cooperative locking parts, and spring actuated means for closing the jaws together when said tripper has been pushed upward to separate said locking parts and means.

7. A presetting grab tool including; a hollow member having means for moving the same, arcuately formed grab jaws pivoted to the lower end of the hollow member, a tripper positioned within the confines of said jaws and having an upwardly extending stem, a spring cooperating with associated parts normally tending to move the jaws to closed position, locking arms carried by said stem for restraining said spring and holding the jaws in open position, and means acting on the stem for holding the tripper and said locking arms in position to be tripped.

8. A presetting grab tool including; a hollow member having means for moving the same, arcuately formed grab jaws pivoted to the lower end of the hollow member, a tripper positioned within the confines of said jaws and having an upwardly extending stem, a spring cooperating with associated parts normally tending to move the jaws to closed position, locking arms carried by said stem for restraining said spring and holding the jaws in open position, and means acting on the stem for holding the tripper and said locking arms in position to be tripped, said hollow member being provided with means whereby an implement may be applied indirectly to the tripper to reset it and its locking arms to "set" position.

9. A presetting grab tool including; a hollow member having means for moving the same, arcuately formed grab jaws pivoted to the lower end of the hollow member, a tripper positioned within the confines of said jaws and having an upwardly extending stem, a centrally located tube having its lower end passing over the upper end of the tripper stem, a disc carried by the tube and having links pivoted to said jaws, a pin, carrying a

collar, fastened to the upper end of the tube, a spring acting on the collar normally tending to move the tube and disc so as to close the jaws, locking means carried by the tripper stem for restraining said spring from action, and a spring within said tube acting on the stem to hold the tripper and locking means in position to be tripped.

10. A grab tool including; a tubular casing having means for moving the same, grab jaws pivoted to the lower end of the casing, said jaws having their outer surfaces formed to conform to the outer contour of the casing when the jaws are in open position, a centrally arranged movable member having levers connected to said jaws, a spring normally tending to move the movable member and jaws to closed position, a tripper supported by said movable member, locking means carried by the tripper for normally holding the movable member against movement due to the spring, means for holding the tripper in holding position, and means provided for presetting the tool in position to grab.

11. A grab tool including a tubular casing having means for moving the same, grab jaws pivoted to the lower end of the casing, said jaws having an abutment against the lower end of said casing, a movable tube centrally positioned within the casing and provided with means connected to said jaws, a spring arranged to act on said tube to normally close the jaws, a tripper carried by said tube and having movable arms cooperating with means supported by the casing for holding the spring in restrained position, and a spring within the tube acting to hold the tripper and arms in locked position.

12. A grab tool including a tubular casing having means for moving the same, grab jaws pivoted to the lower end of the casing, a movable member within the casing and having means connected to said jaws to move the same, a spring, means for transmitting the force of the spring to said movable member which tends to move so as to close the jaws, a tripper supported by said member, means comprising permanent parts of the tool actuated by the tripper for holding said movable member from movement, and means provided for presetting the tool in position to grab.

13. A grab tool including a tubular casing having means for moving the same, grab jaws pivoted to the lower end of the casing, a movable member within the casing and having means connected to said jaws to move the same, a spring acting on said movable member tending to move the jaws to closed position, a second spring and a member slidable upward against the tension of said second spring only for allowing the first spring to function to close the jaws.

14. A grab tool including a casing having attachment means for moving the same, grab jaws pivoted at the lower end of said casing,

a movable member within the casing, means connecting the jaws to said movable member, means continuously acting on said movable member tending to move the jaws to closed position, means acting in conjunction with said movable member for holding the jaws in open position, a member positioned within the tubular casing and slidable upwardly therein, a trigger positioned between said jaws adapted to be moved upwardly by contact with an object to be grabbed by said jaws, means connecting said trigger with said holding means, and means for moving said slidable member upwardly after said holding means has been released.

In testimony whereof, I affix my signature.

NATHAN M. SLOVER.
